UNITED STATES PATENT OFFICE.

ROBERT H. WENTORF, OF WEST BEND, WISCONSIN, ASSIGNOR TO WEST BEND ALUMINUM COMPANY, A CORPORATION OF WISCONSIN.

DESIGN FOR A UTENSIL PAD.

Application filed July 21, 1923. Serial No. 6,818. Term of patent 14 years.

To all whom it may concern:

Be it known that I, ROBERT H. WENTORF, a citizen of the United States, residing at West Bend, in the county of Washington and State of Wisconsin, have invented a new, original, and ornamental Design for Utensil Pad, of which the following is a specification, reference being had to the ac-

companying drawing, forming a part thereof.

The figures are top plan and side elevational views, respectively.

I claim:

The ornamental design for a utensil pad, as shown.

ROBERT H. WENTORF.
